UNITED STATES PATENT OFFICE.

WILLIAM NICHOL, OF DETROIT, MICHIGAN.

INTERNAL-COMBUSTION ENGINE.

1,323,785.

Specification of Letters Patent.

Patented Dec. 2, 1919.

Application filed February 27, 1919. Serial No. 279,522.

To all whom it may concern:

Be it known that I, WILLIAM NICHOL, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

This invention relates to internal combustion engines, and its object is to provide a unique construction by means of which the reciprocal motion of the pistons in the cylinders is transformed into rotary motion. More particularly the object of the invention is to provide a series of cylinders positioned in spaced relation circumferentially about a rotatable element which may serve the purpose of a fly-wheel and pistons movable in the cylinders by the explosive force of an ignited charge, the pistons upon the upper stroke engaging the periphery of the wheel, there being several of said cylinders in which the charge is exploded in succession. A further object of the invention is a construction of the character above outlined in which the pistons are intermittently connected with the rotating element and being supplied with an explosive charge by an injecting device individual to each cylinder. These various objects and the several novel features of the invention are hereinafter more fully pointed out and claimed and the preferred form of the invention is shown in the accompanying drawings in which—

Figure 1 is a side elevation of my improved internal combustion engine.

Fig. 2 is a section taken on line 2—2 of Fig. 1.

Fig. 3 is a detail showing the interior of one of the cylinders and mode of connection of a piston therein with the rotating element.

Fig. 4 is an enlarged section taken on line 4—4 of Fig. 3.

Fig. 5 is a section of one of the charge forming cylinders taken on line 5—5 of Fig. 2.

Fig. 6 is a horizontal section taken on line 6—6 of Fig. 5.

Fig. 7 is a detail of a valve and operating

rod utilized between a pump cylinder and 55 the explosion chamber of one of the cylinders.

Fig. 8 is a section taken on line 8—8 of Fig. 2 showing the eccentric and band for operating the several pump cylinders. 60

In the preferred form of the invention I provide a cylinder casing 1 having an enlargement at the periphery, as will be understood in Fig. 4, to inclose the rim of the fly wheel 2. On the periphery of this cylindrical casing 1 are secured a series of cylinders 3, the longitudinal axis of which is formed on a curve whose axis is equal to the distance between the center of the cylinder and center of the case. As shown in Fig. 1, 70 I have provided four of these cylinders 3, but a greater or less number may be provided as may be desired, and it will be noted from Fig. 4 particularly, that the cylinders are practically round in cross section provided with flanges 4 for bolting to the flanges provided on the periphery of the case 1 which is open at the point of attachment of the cylinder members which closes the said opening. The fly wheel is provided 80 at the periphery with a pair of circumferential grooves 5 and 6 and depending flanges 7 are provided on the cylinder casing extending into these grooves and the inner face of each flange is provided with several 85 packing members 8 which may be of any desired type, preferably spring-pressed members engaging the sides of the central portion 9 of the fly wheel between the two grooves. The two flanges 7 of each cylinder provide an inner slot open through the wall of the cylinder as will be understood from Figs. 3 and 4, and this slot extends nearly the full length of the cylinder, the head end of the cylinder being unprovided 95 with a slot as will be understood from the reference character 10 in the Fig. 3. Thus, at this end a closed explosion chamber is provided into which the explosive charge is initially introduced as is hereinafter shown. 100

This slot formed in the cylinder wall enables the introduction of an arm therethrough in the formation of the cylinder which arm may carry a grinding device or apparatus at the end and the arm from the center of the said apparatus to the end of the arm being of a length equal to the radius of the curve of the longitudinal axis of the cyl-

inder and thus the cylinder may be ground to curved shape as shown. In each of the cylinders is a piston 11 having the usual packing rings 12 thereon and being shaped to ride freely in the cylinder, and each piston is provided with a curved piston rod 13, the free end of which rides in a bracket 14 secured to the casing at one end of the cylinder as shown in Figs. 1 and 3 and on this 10 rod between the bracket and the piston is a compressible spring 15, and also between the bracket and end of the rod is a shock absorbing spring 16. The spring 15, after the piston has been moved by the explosion of 15 a charge at the forward end, is compressed by movement of the piston to normal position shown in Fig. 3, the rebound or shock absorbing spring 16 becoming effective upon the piston reaching its normal position.

20 The periphery of the fly wheel 2 and on the portion 9 between the two circumferential grooves heretofore mentioned is notched as is indicated at 17, there being several of these notches, there necessarily being only 25 one series of notches about the periphery and the pistons are each provided with a latch member 18 which is to be understood (although not here shown) as being spring-actuated tending to force the latch member 30 out through the slot between the flanges 7 of the piston and into engagement with the periphery of the wheel 2 and upon the explosion taking place in the cylinder head, (which is timed to take place at the interval 35 when the series of notches is in about the relationship to the piston as is shown in Fig. 3) the said latch member engages one of the several notches. The charge then being exploded forces the piston outward in 40 its cylinder as above stated and at the finish of the stroke the piston uncovers an aperture 19 in the wall thereof allowing the burned gases to exhaust freely from the cylinder and on relief of pressure the spring 45 15 returns the piston to normal position. It is to be noted that the periphery of the wheel 2 is spaced slightly from the outer periphery of the case 1 and in order to prevent leakage of an explosive charge through 50 the slot between the flanges 7 and into this space between the periphery of the wheel and outer periphery of the case, I provide a bar 20 carried by an inwardly projecting portion on the piston and extending 55 from one flange 7 to the other flange. This is preferably a spring-pressed bar riding in contact with the face of the wheel which should be finished for this purpose and the bar, being longer than the notches 17 in 60 the wheel, has no tendency to drop into the said notches as will be understood from Fig. 4. I also provide a packing member 21 at the forward end of the cylinder and the said packing members 20 and 21 and 65 the upper members 8 on the flanges 7 of

the cylinder localize the exploding gases and prevent dissipation of the force thereof about the periphery of the wheel.

As will be understood from Figs. 1 and 2, each explosion cylinder is provided with 70 a pump cylinder 22 positioned radially of the casing 1. Each of these pump cylinders is provided with a valve 23 in the head thereof opening on the outward stroke of the piston 24 in each cylinder and closing 75 on inward movement thereof. As shown by dotted lines in Fig. 1, I provide a carburetor 25 preferably about centrally located and independently connected with the intake port of each pump cylinder by a 80 manifold 26 connected with the carburetor. The pistons 24 of each cylinder are connected by a rod 27 with an eccentric band 28 on the eccentric 29 secured to the central shaft 30 on which the wheel 1 is mounted 85 and rotation of the eccentric 29 causes a successive movement of the pistons in the pump cylinders 22. The eccentric member 29 has a cam 31 formed at one side thereof and each pump cylinder is provided at one side with a spring-controlled valve rod 32 having a roller at the inner end riding on the cam. This valve rod has a flat portion provided with an aperture 32a and the cam is so positioned relative to the 90 eccentric that as the piston in a pump cylinder begins its intake stroke the conduit 33 leading from the pump cylinder to the explosion cylinder is closed as will be understood from the drawing at the left of Fig. 100 2. Also, as the cylinder is moved to position shown at the right of Fig. 2, the aperture 32a registers with the conduit 33 and allows the charge taken into the pump cylinder by the previous movement of the piston to be discharged into the closed explosion chamber formed at the head of the piston. By this mechanism each of the explosion cylinders are provided in succession 105 with an explosive charge, the relationship 110 of the several elements being readily understood from Figs. 1 and 2.

In order that ignition of the charge in the cylinder shall be produced at a time when the notches 17 are in position to be 115 engaged by the latch member 18 of the piston, I provide a commutator which may be of any approved form but is here shown as being a ring member 34 indicated by dotted lines in Fig. 1 and carrying a roller 35 on 120 the periphery thereof, and each of the valve rods 27 may be provided with a spring contact member 36 adapted to be engaged by the roller 35, the electric wiring being such that, upon contact of the roller 35 with 125 the spring member 36, electric discharge takes place in the head of the cylinder individual to the said rod, there being a spark plug 37 electrically connected with the contact member 36 in each instance and thus 130

the time of the explosion may be accurately determined by the positioning of the relation to the cams on the periphery of the wheel 34 and the charge ignited at the time 5 when the notches 17 are in position to be engaged by the latch member 18. If the surface speed of the wheel becomes too great preventing the latch member from engaging a notch, the surface would necessarily 10 become decreased until the piston in its movement may engage and drive the wheel. The notches are shaped to allow the latch member 18 to draw out of the same on movement of the wheel away from the latch 15 member in its designed direction of rotation.

I claim—

1. In an internal combustion engine, a rotor, a stator, a series of longitudinally 20 curved cylinders positioned about the periphery of the stator, the cylinder wall having a slot, a piston in each of the said cylinders, means for providing and exploding an explosive charge in the cylinders to drive the 25 pistons, the rotor having a series of notches in the periphery and each piston having a latch member adapted to engage in the notches on movement of the pistons under the explosive force, means for exhausting 30 the exploded charge at the finish of the stroke of the piston, and a spring returning the piston to original position.

2. In an internal combustion engine, a rotor, a stator, a series of cylinders substantially 35 equidistantly positioned about the periphery of the stator, each cylinder wall having a slot, the stator being correspondingly slotted, a piston in each of the said cylinders, means for providing an explosive charge in the cylinders to drive the pistons, the rotor having a single series of notches on the periphery, a latch member on 40 each of the pistons adapted to engage in the notches, means for firing a charge in each 45 piston at the time the notches of the rotor are positioned for engagement of the latch therein, means for exhausting the exploded charge at the completion of the movement of the piston, and a spring returning the piston 50 to original position.

3. In an internal combustion engine, a rotor, a stator, a series of longitudinally curved cylinders concentrically positioned relative to the rotor, each cylinder wall having a slot and the stator being correspondingly slotted, a piston in each of the cylinders, a latch member for each piston extending through the said slot to engage the rotor, the rotor being notched, packing 55 means for preventing dissipation of the exploded charge through the slot, means for providing an explosive charge for the cylinders in succession, and a spring compressed on outward movement of the piston adapted 60 to return the pistons to original position.

4. In an internal combustion engine, a stationary case, a fly wheel rotatably mounted therein, a series of cylinders equidistantly positioned about the periphery of the case, the cylinders being curved longitudinally, the axis of which is equal to the distance of the center of the cylinder from the axis of the fly wheel, a piston in each cylinder, a rod connected to each piston, a bearing for the rod, a spring between the 70 bearing and piston head compressed by movement of the piston outwardly in the cylinder and adapted to return the piston to normal position, each cylinder wall and casting at the point of support of the cylinder 75 having a peripheral slot, a spring-projected latch member on each piston extending through the notch to contact the periphery of the fly wheel, said fly wheel periphery having a series of notches adapted to be 80 engaged by the latch member, means for supplying an explosive charge to the cylinders in succession, and means for igniting the charge to cause outward movement of the piston when the said notches are in position to be engaged by the latch member. 85

5. In an internal combustion engine, a stator, a rotor therewithin, a series of longitudinally curved cylinders on the periphery of the stator, the axis of which is equal to the 90 distance between the center of the cylinder and the center of the rotor, the cylinders each having a pair of spaced inwardly projecting flanges, circumferential grooves in the rotor in which the flange of each cylinder rides, packing members in the said groove between the inner face of the flange and face of the groove, a stationary packing member on the stator engaging the periphery of the rotor between the flanges, a 100 piston in each cylinder having an inwardly projecting part near the forward end, a packing member on said part engaging the periphery of the rotor between the flanges, a spring-pressed latch member connected to 105 the piston and extending between the said flanges of the cylinders to engage the periphery of the rotor, a series of notches in the periphery of the rotor with which the latch member may engage, means for providing a compressed charge for the cylinders, means for firing the charges in succession to force the piston outward in the cylinder and drive the rotor, an exhaust port 110 opened by the piston near the completion of its outward movement to exhaust the burned gases, and a spring compressed by said outward movement of the piston and adapted to return the same to position for succeeding 115 operations. 120

6. In an internal combustion engine, a stator, a rotor whose axis coincides with the axis of the stator, a series of cylinders equidistantly positioned about the periphery of the stator, a piston in each cylinder adapted 130

to be driven outwardly therein, a spring placed under tension by said piston movement and adapted to automatically return the piston to original position, means for connecting the piston with the rotor during its outward movement to drive the rotor, and means for supplying a compressed explosive charge to the cylinder consisting of a pump cylinder, a carbureter connected therewith, a piston reciprocable in the cylinder to provide a charge and compress

the same, a conduit between the pump cylinder and forward end of the companion explosion cylinder, a valve controlling the conduit, means for operating the valve to open 15 the same to introduce the charge in the explosion chamber, and means for firing the charges in the cylinders in succession.

In testimony whereof, I sign this specification.

WILLIAM NICHOL.
